UNITED STATES PATENT OFFICE

139,081

DESIGN FOR A FLAG

Ida Hambrock, Toledo, Ohio

Application June 6, 1944, Serial No. 113,869

Term of patent 14 years

(Cl. D29—17)

To all whom it may concern:

Be it known that I, Ida Hambrock, a citizen of the United States of America, residing in the city of Toledo, in the county of Lucas and State of Ohio, have invented a new, original, and ornamental Design for a Flag, of which the following is a specification, reference being had to the accompanying drawing, forming a part thereof.

The figure is a front elevation of a flag, showing my new design.

I claim:

The ornamental design for a flag, as shown.

IDA HAMBROCK.
